ISRAEL E. BRETZFELDER, MAURICE K. BRETZFELDER, AND JOSEPH SHADY, OF NEW YORK, N. Y., ASSIGNEES TO KRAKAUER BROS., OF NEW YORK, N. Y., A CORPORATION OF NEW YORK.

PIANO-LOCKING DEVICE.

Application filed January 16, 1924. Serial No. 686,572.

To all whom it may concern:

Be it known that we, ISRAEL E. BRETZFELDER, a citizen of the United States, and a resident of the city of New York, borough of Manhattan, in the county and State of New York, MAURICE K. BRETZFELDER, a citizen of the United States, and a resident of the city of New York, borough of Manhattan, in the county and State of New York, and JOSEPH SHADY, a citizen of the United States, and a resident of the city of New York, borough of the Bronx, in the county of Bronx and State of New York, have invented a new and Improved Piano-Locking Device, of which the following is a full, clear, and exact description.

This invention has relation to locking devices and has particular reference to a device for locking pianos.

In reproducing grand pianos, the roll or record, tracker bar and the controls therefore are installed in a sliding drawer arranged below the keyboard. At the present time no means is provided for locking the drawer in its closed position whereby the lock in general use may be used to perform a dual function.

As a further object the invention contemplates in a locking means of the character set forth a mechanism by virtue of which the point of engagement of the drawer locking means with its keeper may be carried to any desired or appropriate portion of the drawer in order to conceal the keeper opening when the drawer is in open position.

Furthermore the invention comprehends in a reproducing grand piano a common means for locking the top, the fall and the drawer which contains the controls and tracker bar in a closed position, thereby eliminating the necessity of employing a plurality of lock mechanisms for the purpose.

As a still further object the invention aims to provide a locking attachment for the drawer of a reproducing grand which is comparatively simple in its construction, inexpensive to manufacture, and which is highly efficient in its purpose.

With the above recited and other objects in view, the invention resides in the novel construction set forth in the following specification, particularly pointed out in the appended claims and illustrated in the accom-

panying drawings, representing one embodiment of the inventive concept. 55

In the drawings—

Figure 1 is a fragmentary vertical sectional view through a reproducing grand equipped with a drawer locking attachment 60 constructed in accordance with the invention and illustrating the same in its locked position.

Fig. 2 is a detail perspective view of the locking attachment removed. 65

Referring to the drawings by characters of reference, 10 designates generally a reproducing grand which is provided with the usual hinged top 11, front board 12 and pivoted fall or keyboard cover 13. In this type of piano the controls, the tracker board and the like are arranged within a drawer 14 which is mounted to slide beneath the lower wall 15 of the keyboard housing. The downwardly projectable locking bolt 16 is mounted in the front board and is movable respectively to locked and unlocked position by means of a key actuated lock mechanism 17 embedded in the depending cleat 18 at the forward portion of the top 11. The lock mechanism 17 in addition to projecting and retracting the lower end of the locking bolt 16 serves to connect and lock the top in its closed position. These locks are of the common well known type and do not directly form a part of the present invention. 75

The locking attachment for simultaneously locking the drawer 14 in closed relation when the fall 13 is closed and locked, 90 consists essentially of a locking bolt 20 projectable below the bottom wall 15 of the keyboard housing and into a keeper opening 21 in the drawer 14 and a pressure element 22 which is operatively connected with the locking bolt 20 and which is normally projected upwardly by a spring 23 above the upper edge of the vertical wall 24 of the keyboard housing where it is engaged by the fall when the same is swung to its closed position. The spring 23 serves in addition to projecting the pressure member 22 above the upper edge of the wall 24, to further retract or lift the locking bolt 20 from its keeper opening 21 whereby the 100 drawer is unlocked or released. 105

In the preferred embodiment of the invention it is desirable to space the keeper open-

ing from the front of the drawer a sufficient distance whereby the same will not be exposed to view when the drawer is open and for this reason the locking bolt 20 is carried 5 by or constitutes the downturned end of the arm 25 at the rear end of a shaft 26, the forward end of which is provided with a corresponding arm 27. The shaft 26 is mounted in bearings 28 arranged in a groove 10 in the under side of the lower wall 15 of the keyboard housing and the free end of the forward arm 27 is mounted for movement in a transversely arranged communicating groove 29. The free end of the arm 15 27 is provided with a flattened apertured head 30 through which a stem 31 extends, said stem being secured to the pressure member 22. The lower end of the stem is formed 20 with stops or abutments 32 and 33 disposed below and above the head 30.

In use and operation, when the top 11 and fall 13 are arranged in closed position as illustrated in Fig. 1 with the locking mechanism connecting the top with the 25 front board 12 and with the lower projected end of the locking board 16 in rear of the upper edge of the fall 13, the pressure element 22 will be moved downwardly thereby effecting a partial rotation of the shaft 16 30 and simultaneous downward swinging movements of the arms 27 and 25. This engages the locking element 20 in the keeper opening 21 of the drawer whereby manual or mechanical operation of the piano is precluded.

35 We claim:

1. In a reproducing grand piano which includes a drawer disposed below the key-board housing and containing the controls and tracker board of the player mechanism, the combination with the locking mechanism which locks the top and key-board cover in closed position, of locking means for said

drawer comprising a keeper opening formed in the drawer, a shaft having angularly disposed front and rear arms, the latter having a locking terminal engageable within the keeper opening upon downward swinging movement of said arm, a plunger connected with the free end of the front arm, means normally projecting the upper end 45 of the plunger into the path of movement of the key-board cover when moved to closed position and effecting the upward swing of the rear arm to disengage the locking terminal from the keeper opening whereby said key-board cover when locked in a closed condition by the locking mechanism, cooperates with said locking means to cause the same to lock the drawer.

2. The combination with a reproducing 60 grand piano which includes a drawer disposed below the key-board housing and containing the controls and tracker bar of the player mechanism, and a locking mechanism for locking the top and key-board cover, of 65 drawer-locking means including a keeper opening formed in the drawer, a latch comprising a shaft having front and rear angularly disposed arms, the rear arm having a locking terminal engageable in the keeper 70 opening upon downward swinging movement of the rear arm, a plunger connected to the free end of the front arm extending upwardly and engageable by the key-board cover when swung to closed position for effecting locking engagement of the rear arm 75 terminal in the keeper opening, and means for normally projecting the plunger upwardly to turn the shaft for disengaging the locking terminal from the keeper opening.
